US00D432982S

United States Patent [19]

Miyashita

[11] Patent Number: Des. 432,982

[45] Date of Patent: ** Oct. 31, 2000

[54] RECHARGEABLE BATTERY

[75] Inventor: **Shin Miyashita**, Tokyo, Japan[73] Assignee: **Sony Corporation**, Japan

[**] Term: 14 Years

[21] Appl. No.: 29/099,985

[22] Filed: Feb. 1, 1999

[51] LOC (7) Cl. 13-02

[52] U.S. Cl. D13/103

[58] Field of Search D13/103; 429/96-100,
429/156, 163, 174

[57] CLAIM

The ornamental design for a rechargeable battery, shown and described.

DESCRIPTION

FIG. 1 is a perspective view of a first embodiment of a rechargeable battery showing my new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a rear elevational view thereof; and

FIG. 7 is a bottom plan view thereof.

FIG. 8 is a perspective view of a second embodiment of a rechargeable battery showing my new design.

FIG. 9 is a top plan view thereof;

FIG. 10 is a left side elevational view thereof;

FIG. 11 is a front elevational view thereof;

FIG. 12 is a right side elevational view thereof;

FIG. 13 is a rear elevational view thereof; and

FIG. 14 is a bottom plan view thereof.

FIG. 15 is a perspective view of a third embodiment of a rechargeable battery showing my new design;

FIG. 16 is a top plan view thereof;

FIG. 17 is a left side elevational view thereof;

FIG. 18 is a front elevational view thereof;

FIG. 19 is a right side elevational view thereof;

FIG. 20 is a rear elevational view thereof; and

FIG. 21 is a bottom plan view thereof.

FIG. 22 is a perspective view of a fourth embodiment of a rechargeable battery showing my new design;

FIG. 23 is a top plan view thereof;

FIG. 24 is a left side elevational view thereof;

FIG. 25 is a front elevational view thereof; and

FIG. 26 is a right side elevational view thereof.

FIG. 27 is a rear elevational view thereof; and,

FIG. 28 is a bottom plan view thereof.
